UNITED STATES PATENT OFFICE.

THOMAS M. MYERS, OF NEW YORK, N. Y., ASSIGNEE TO ADDIFFREN REFRIGERATING MACHINE COMPANY, A CORPORATION OF NEW JERSEY.

REFRIGERATING APPARATUS.

1,193,874.

Specification of Letters Patent. Patented Aug. 22, 1916.

Application filed April 9, 1914. Serial No. 550,628.

To all whom it may concern:

Be it known that I, Thomas M. Myers, a citizen of the United States, residing at New York city, county of New York, and State of New York, have invented certain new and useful Improvements in Refrigerating Apparatus; and I do hereby declare the following to be a full, clear, and exact description of the invention, such as will enable others skilled in the art to which it appertains to make and use the same.

This invention relates to refrigerating apparatus of the character consisting of a closed container for a refrigerant which is liquefied in one portion of the container while giving off heat and subsequently vaporized in another portion of the container while absorbing heat from the surrounding medium. Apparatus of this character is commonly made in the form of a rotatable closed container consisting of two compartments, in one of which the refrigerant is liquefied and in the other of which the vaporization of the refrigerant takes place, the container having devices therein for effecting the circulation and liquefying of the refrigerant and the circulation of a suitable lubricant for the operating mechanism.

In apparatus of this character, it is desirable that the vaporizing compartment of the closed container should have a very large superficial area in order that the absorption of heat from the surrounding medium may take place with a high degree of efficiency. In some cases, this vaporizing compartment is partially or wholly immersed in a liquid to be cooled, but in other cases, the apparatus is used for cooling air, the air being circulated upon the surface of the vaporizing compartment. When the apparatus is used for cooling air in this manner, the construction of the vaporizing compartment so as to present an extended superficial area, is of even greater importance.

The present invention involves the provision of an improved construction of apparatus of this character with reference particularly to the structure of the vaporizing compartment. In order to provide a greatly enlarged exterior surface on the vaporizing compartment, the latter is made to consist in part of a coil of tubing through which the refrigerant is caused to flow. Preferably, the convolutions of this coil are spaced apart an amount sufficient to permit the free cir-

culation of the medium to be cooled within and about the several convolutions, so that the entire exterior surface of the tubing is effective in the absorption of heat. Preferably the coil is arranged coaxially with the rotatable vaporizing compartment, and the several convolutions thereof are of constant or constantly increasing diameter from the inlet end to the outlet end. By reason of this arrangement of the coiled tubing the refrigerant, whether in liquid or vapor form, will readily flow through the tubing from one end thereof to the other. If desired, the spaces within the coiled tubing may be employed in increasing the exterior surface of the vaporizing compartment by providing thereto an extension which projects into or through the coiled tubing, and the device for conveying the liquid refrigerant may be arranged to deposit more or less of the refrigerant upon the surface of this extension where vaporization and absorption of heat will take place.

The invention of special utility in connection with refrigerating apparatus of the type shown in Patent No. 1,155,796 to Addiffren and Myers.

The preferred embodiment of the invention is illustrated in the accompanying drawings, in which

Figure 1 is a central vertical section through the apparatus; Fig. 2 is an end view of the vaporizing compartment broken away in part; Fig. 3 is a detail view in transverse section showing a section of the mechanism within the liquefying compartment, and Fig. 4 is a view in section of a modified form of vaporizing compartment.

Referring to these drawings, the complete refrigerating apparatus is shown in Fig. 1. This includes a closed container having the shape of a dumb bell. It consists of two enlarged end portions connected by a rigid tube, the whole being rotatable in suitable bearings. The end portion 5 constitutes the liquefying compartment and the end portion 6 the vaporizing compartment. The liquefying compartment is mounted for rotation within a suitable receptacle 7 and is partially immersed in a liquid therein which is constantly drawn off and replenished through pipes 8.

Within the liquefying compartment is a pump 9 which draws vapor into the liquefy-

ing compartment from the vaporizing compartment 6 through a tube 10 connecting the two compartments and rigidly secured thereto. This pump 9, or compressor, 5 presses the vapor and the latter, due to its compression and absorption of heat by the water in the receptacle 7, becomes transformed into a liquid. This liquid is carried around by the rotation of the compartment 5, is taken up by a suitable collector, and collects within a receptacle 11 formed in the structure which supports the pump 9. From this receptacle 11, the liquid refrigerant passes through a tube 12 10 concentric with the tube 10 into the vaporizing compartment 6. The frame which supports the pump is weighted, so that it remains stationary, while the compartments 5 and 6 and the pipe 10 connecting them are 15 rotated by power applied to a pulley 13, and this relative rotation of the parts effects the operation of the pump 9 by means of an eccentric 14, which is keyed to the end of the tube 10 lying within the liquefying 20 compartment 5. Within the liquefying compartment is a centrifugally operated valve 15 shown in detail in Fig. 3 by which an equalizing port in tube 10 is opened when the apparatus is not in use.

25 The vaporizing compartment 6 is secured to the tube 10 so as to rotate therewith, and within it is a collector and separator 16 which is secured to the tube 12 so that it does not partake of the rotation of the vaporizing 30 chamber 6. The collector and separator 16 is arranged to collect the lubricant and the refrigerant which is carried around by the rotation of the vaporizing chamber 6. The liquid thus collected is separated, the lubricant 35 is allowed to flow back into the liquefying compartment through the tube 10, and the liquid refrigerant is circulated upon the walls of the vaporizing compartment through tubes 17 and 18 projecting laterally 40 from the collector 16.

45 All of the parts so far described may be identical in construction with those illustrated and described in the application above referred to, and therefore a more detailed description is unnecessary.

The vaporizing compartment 6 is here shown as inclosed within a suitable receptacle 19. This may be a receptacle for a liquid to be cooled, the liquid being maintained at such a level in the receptacle that the vaporizing compartment is partially immersed therein. If desired, the apparatus may be employed for cooling air, in which case the vaporizing compartment 6 need not be inclosed, and means may be provided for causing a circulation of air upon the vaporizing compartment.

50 The vaporizing compartment is shown as formed by two shells which are secured together, and one of which is secured to the

end of tube 10. It is provided with a lateral extension as shown at 20, by means of a piece which is of conical shape and which has its larger end secured to and in open communication with one of the shells of the compartment proper. At its smaller end, this conical extension 20 has a cap or end piece 21 formed integral therewith. Between this end piece and the compartment 6 are one or more lengths of coiled tubing 70 through which the liquid refrigerant flowing from the liquefying compartment 5 is adapted to flow. Each coil of tubing is of constant or constantly increasing diameter from the inlet end to the outlet end thereof, 75 so that the refrigerant, whether in the form of vapor or liquid, will readily flow in the manner required. In the present instance three lengths of coiled tubing are provided, these being arranged in parallel between the end piece 21 and the compartment 6. The tube 12 through which the liquid refrigerant flows to the vaporizing compartment is extended through the compartment 6 and the collector 16 and out to the end piece 21 to which its extreme end is secured. Adjacent to its end, the tube 12 is provided with two or more openings 22 and 23. The opening 22 is located in alignment 80 with the end piece 21, and the opening 23 is located within the conical extension 20 and a short distance from the smaller end thereof. The space within the extension 20 is enlarged slightly within the end piece 21, and this space communicates with three outlets, each of which is designed to receive the end of one of the three lengths of tubing 24, 25 and 26. The convolutions of these three coiled tubes are shown as of constantly increasing diameter from the inlet ends thereof at the end piece 21 to the outlet ends which are secured to the vaporizing compartment 6. To facilitate this connection to the compartment 6, the latter is formed to provide three bosses, into which the ends 90 of the tubes are received. The end piece 21 is preferably provided with a movable plug 27 in the end thereof, opposite the end of the tube 12. As shown in Fig. 1, the duct 18 leading from the collector 16 is preferably 95 extended well into the conical extension 21, so that the liquid refrigerant issuing therefrom is caused to flow over a substantial portion of the interior surface of the extension 20.

100 In operation, the liquid refrigerant admitted to the tube 12 from the receptacle 11 flows through the tube from end to end and passes out through the openings 22 and 23. Such of the liquid as passes out through the opening 23 flows upon the wall of the conical extension 20 and passes along that wall until it reaches the compartment 6. During its passage through the extension 20, it is 105 constantly absorbing heat from the sur- 110

rounding medium and more or less of it is vaporized. In addition to the liquid admitted to the extension 20 in this manner, the liquid refrigerant is taken up by the collector 16 and flows through the duct 18 into the extension 20. The refrigerant which passes through the duct 12 and out through the opening 22 passes into the coiled tubes 24, 25 and 26 through the inlet ends of those tubes which are secured to the end piece 21. This refrigerant passes through these coiled tubes and into the compartment 6. In so doing, it is distributed over an extended area and is therefore the more effective in absorbing heat.

It will be seen that the tubes 24, 25 and 26, and the extension 20 of the vaporizing compartment, present a very large superficial area. Because of this, the efficiency of the apparatus in absorbing heat from the surrounding medium is greatly increased. By reason of this increased area, the apparatus may be effectively employed in cooling air.

It will be noted that the adjacent convolutions of the coiled tubes are spaced apart slightly so that air or other medium to be cooled, may readily pass within the coiled tubes and in contact with the inner sides thereof and the walls of the extension 20.

30 In order that the refrigerant may flow readily in the coil of tubing, the connection of the tubing to the liquefying compartment should be at or near the axis of the coil, and the connection to the vaporizing compartment should be at or near the periphery of the coil, and the coil should be of constant or constantly increasing diameter from the inlet end thereof to the outlet end where the refrigerant enters the vaporizing compartment. In Figs. 1 and 2, the coil is shown as of constantly increasing diameter, and this is the construction which I prefer to employ. The coil may, however, be of constant diameter, and such a construction is shown in Fig. 4. In this figure, the vaporizing compartment is shown at 28 secured to the tube 10, but it is not provided with an extension such as that shown at 20 in Fig. 1. Instead the end of the piece of tubing is bent around 50 within the coil and extends in the direction of the axis of the coil back to the vaporizing compartment 28. This end 29 of the coil of tubing is secured within a boss 30 formed on the wall of the compartment 28 and extends 55 in the direction of the axis of rotation to a point adjacent to the distant end of the coil of tubing 31. A single length of tubing is employed in this instance instead of three pieces as shown in Fig. 1, and the convolutions 60 are spaced apart a substantial distance so that the medium to be cooled may readily flow within and around the several convolutions. In other respects the construction represented in Fig. 4 may be similar to that 65 shown in Fig. 1.

What I claim is:

1. In an inclosed refrigerating apparatus containing a refrigerant in liquid and vapor states, a liquefying compartment, a vaporizing compartment, a coiled tube connected at one end to the vaporizing compartment, means for carrying liquid from the liquefying compartment to the other end of the tube and a collector within the vaporizing compartment; substantially as described. 75

2. In an inclosed refrigerating apparatus containing a refrigerant in liquid and vapor states, a liquefying compartment, a vaporizing compartment, a coiled tube in axial alignment with the vaporizing compartment 80 and connected at its outlet end thereto, means for carrying liquid from the liquefying compartment through the vaporizing compartment and the coiled tube to the inlet end of the tube, and a collector within the vaporizing compartment; substantially as described.

3. In an inclosed refrigerating apparatus containing a refrigerant in liquid and vapor states, a liquefying compartment, a vaporizing compartment, a coil of tubing connected at its inlet end and near its axis to the liquefying compartment and at its outlet end and near its periphery to the vaporizing compartment, the convolutions of the coil 95 being of constant or constantly increasing diameter from its inlet end to its outlet end, and means for drawing the vaporized refrigerant from the vaporizing compartment into the liquefying compartment; substantially as described.

4. In an inclosed refrigerating apparatus containing a refrigerant in liquid and vapor states, a liquefying compartment, a vaporizing compartment, a coil of tubing connected at its outlet end and near its periphery to the vaporizing compartment, and means for conducting the liquid from the liquefying compartment into the coil of tubing near its axis, the convolutions of the coil 110 having a constant or constantly increasing diameter from the inlet to the outlet end thereof; substantially as described.

5. In an inclosed refrigerating apparatus containing a refrigerant in liquid and vapor states, a liquefying compartment, a vaporizing compartment, a plurality of coiled tubes arranged in parallel and connected at their outlet ends to the vaporizing compartment, means for carrying liquid from the liquefying compartment to the inlet ends of said tubes and a collector within the vaporizing compartment; substantially as described.

6. In an inclosed refrigerating apparatus containing a refrigerant in liquid and vapor states, the combination of a liquefying compartment, a vaporizing compartment, a plurality of coiled tubes arranged in parallel and connected at their outlet ends and near

- their peripheries to the vaporizing compartment, and means for conducting the liquid from the liquefying compartments into the tubes near the axis of the coils, the convolutions of the coils being of constant or constantly increasing diameter from the inlet to the outlet end thereof; substantially as described.
7. In a refrigerating apparatus of the character described, the combination of a vaporizing compartment, a coiled tube connected at its outlet end and near its periphery to the vaporizing compartment, an extension on the vaporizing compartment extending within said coiled tube, and means for conducting liquid to the inlet end of said tube and to the end of said extension distant from the vaporizing compartment; substantially as described.
8. In an inclosed refrigerating apparatus of the character described, the combination with a vaporizing compartment, a plurality of coiled tubes arranged in parallel and connected at their outlet ends and near its peripheries to the vaporizing compartment, an extension on the vaporizing compartment extending within said coiled tubes, and means for conducting liquid to the inlet ends of said tubes and to the end of said extension distant from the vaporizing compartment, the convolutions of the coils being constant or constantly increasing diameter from the inlet to the outlet ends thereof; substantially as described.
9. In a refrigerating apparatus of the character described, the combination of a vaporizing compartment, a coiled tube connected at its outlet end to the vaporizing compartment, an extension on the vaporizing compartment extending within said tube, means for conducting liquid to the inlet end of said tube, a collector within the vaporizing compartment, and a duct leading from the collector within said extension; substantially as described.
10. In a refrigerating apparatus of the character described, the combination of a liquefying compartment, a vaporizing compartment, a tube extending from the liquefying compartment through and beyond the vaporizing compartment, and a coiled tube connected at one end to the end of said tube and at the other end to the vaporizing compartment; substantially as described.
11. In a refrigerating apparatus of the character described, a liquefying compartment, a vaporizing compartment, a tube extending from the liquefying compartment through and beyond the vaporizing compartment, an end piece secured to the end of said tube, and a plurality of coiled tubes connected at their inlet ends to said end piece and at their outlet ends to the vaporizing compartment; substantially as described.
12. In a refrigerating apparatus of the character described, a liquefying compartment, a vaporizing compartment, means for rotating the two compartments, an extension on the vaporizing compartment projecting therefrom in the direction of the axis of rotation, a tube extending from the liquefying compartment through the vaporizing compartment and said extension, a coil of tubing connected at one end to the end of said extension distant from the vaporizing compartment and in communication with the adjacent end of said tube and having the other end thereof connected to the vaporizing compartment, a collector within the vaporizing compartment and a duct for liquid refrigerant projecting from the collector into said extension; substantially as described.

In testimony whereof I affix my signature, in presence of two witnesses.

J. M. JACOB

their peripheries to the vaporizing compartment, and means for conducting the liquid from the liquefying compartments into the tubes near the axis of the coils, the convolutions of the coils being of constant or constantly increasing diameter from the inlet to the outlet end thereof; substantially as described.

7. In a refrigerating apparatus of the character described, the combination of a vaporizing compartment, a coiled tube connected at its outlet end and near its periphery to the vaporizing compartment, an extension on the vaporizing compartment extending within said coiled tube, and means for conducting liquid to the inlet end of said tube and to the end of said extension distant from the vaporizing compartment; substantially as described.

20 8. In an inclosed refrigerating apparatus of the character described, the combination with a vaporizing compartment, a plurality of coiled tubes arranged in parallel and connected at their outlet ends and near its peripheries to the vaporizing compartment, an extension on the vaporizing compartment extending within said coiled tubes, and means for conducting liquid to the inlet ends of said tubes and to the end of said extension distant from the vaporizing compartment, the convolutions of the coils being constant or constantly increasing diameter from the inlet to the outlet ends thereof; substantially as described.

35 9. In a refrigerating apparatus of the character described, the combination of a vaporizing compartment, a coiled tube connected at its outlet end to the vaporizing compartment, an extension on the vaporizing compartment extending within said coiled tube, means for conducting liquid to the inlet end of said tube, a collector within the vaporizing compartment, and a duct leading from the collector within said extension; substantially as described.

45

10. In a refrigerating apparatus of the character described, the combination of a liquefying compartment, a vaporizing compartment, a tube extending from the liquefying compartment through and beyond the vaporizing compartment, and a coiled tube connected at one end to the end of said tube and at the other end to the vaporizing compartment; substantially as described.

11. In a refrigerating apparatus of the character described, a liquefying compartment, a vaporizing compartment, a tube extending from the liquefying compartment through and beyond the vaporizing compartment, an end piece secured to the end of said tube, and a plurality of coiled tubes connected at their inlet ends to said end piece and at their outlet ends to the vaporizing compartment; substantially as described.

12. In a refrigerating apparatus of the character described, a liquefying compartment, a vaporizing compartment, means for rotating the two compartments, an extension on the vaporizing compartment projecting therefrom in the direction of the axis of rotation, a tube extending from the liquefying compartment through the vaporizing compartment and said extension, a coil of tubing connected at one end to the end of said extension distant from the vaporizing compartment and in communication with the adjacent end of said tube and having the other end thereof connected to the vaporizing compartment, a collector within the vaporizing compartment and a duct for liquid refrigerant projecting from the collector into said extension; substantially as described.

In testimony whereof I affix my signature, in presence of two witnesses.
